CLAIM

The ornamental design for a reverse trike, as shown and described.

DESCRIPTION

FIG. 1 is a front elevational view of a reverse trike showing my new design;

FIG. 2 is a left side elevation view thereof;

FIG. 3 is a rear elevation view thereof;

FIG. 4 is a right side elevation view thereof;

FIG. 5 is a top plan view thereof;

FIG. 6 is a top, front, and right side perspective view thereof;

FIG. 7 is a top, rear, and left side perspective view thereof;

FIG. 8 is a top, front, and left side perspective view thereof; and,

FIG. 9 is a top, rear, and right side perspective view thereof. The broken lines in the drawings illustrate portions of the reverse trike that form no part of the claimed design.
